UNITED STATES PATENT OFFICE.

BENNO VOM EIGEN, OF NEWARK, NEW JERSEY, ASSIGNOR TO AUG. GOERTZ & CO., A CORPORATION OF NEW JERSEY.

LOCK FOR PURSE OR BAG FRAMES.

No. 911,386.

Specification of Letters Patent.

Patented Feb. 2, 1909.

Application filed September 9, 1908. Serial No. 452,249.

To all whom it may concern:

Be it known that I, BENNO VOM EIGEN, a citizen of the United States, residing at Newark, in the county of Essex and State 5 of New Jersey, have invented certain new and useful Improvements in Locks for Purse or Bag Frames; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification.

My present invention has reference, generally, to improvements in locks for purse or bag-frames, and the like; and the invention has for its principal object to provide a neat 20 and simply constructed lock of the general character hereinafter more fully set forth, and the parts of which can be readily arranged in their assembled and operative relations, and are readily manipulated in the 25 manner as will hereinafter more fully appear.

Other objects of this invention not at this time more particularly enumerated will be clearly understood from the following detailed description of this invention.

With the various objects of my present invention in view, the same consists, primarily, in the novel bag-lock, and its key-operated mechanism therefor; and, the invention consists, furthermore, in the novel arrangements and combinations of devices and parts, as well as in the details of the construction of the same, all of which will be hereinafter more fully described, and then finally embodied in the clauses of the claims, which are appended to and which form an essential part of the specification.

The invention is clearly illustrated in the accompanying drawings, in which:—

Figure 1 is a front view of portions of the two bag-frame sections in their closed relation with a front view of the bag-lock, embodying the principles of the present invention, arranged and secured upon one of the 50 said bag-frame sections; and Fig. 2 is a top or plan view of the said parts shown in Fig. 1, all of the parts of the lock being represented in their normally locked positions. Fig. 3 is a view similar to Fig. 2, 55 showing the key-operated releasing mem-

ber of the lock turned into a plane at right angles to that indicated in said Fig. 2, so as to release a pair of sliding bolts; and Fig. 4 is a similar view showing the said sliding bolts operated and the holding or retaining hook-shaped members of the other frame-sections released from the holding-members or posts of the lock-mechanism. Fig. 5 is a bottom view of the lock, shown detached from the bag-frame section. Fig. 6 is a longitudinal vertical section taken on line 6—6 in Fig. 2 of the drawings, showing the various parts in their normally locked relations, and illustrating in connection with said view, in side elevation, a key about to 70 be inserted in its operative engagement with the oscillatory bolt or releasing-member or post; and Fig. 7 is a similar sectional representation of the same parts, said section being taken on line 7—7 in Fig. 3 of the drawings, and showing the oscillatory bolt-retaining member or post turned into a plane at right angles from that indicated in Fig. 6, so as to release the sliding bolts, said view showing also in connection therewith, and in end 75 elevation, the key for operating the said bolt-releasing member about to be brought in operative engagement with said oscillating bolt-receiving member. Fig. 8 is a longitudinal vertical section of the same parts, the said 80 section being taken on line 8—8 in Fig. 4 of the drawings and showing in connection therewith, in section, the retaining or holding hooks of the other frame-section disengaged from the engaging or locking posts 85 or members of the sliding bolts. Fig. 9 is a transverse vertical section taken on line 9—9 in Fig. 6; Fig. 10 is a similar section taken on line 10—10 in said Fig. 6; and Fig. 11 is a horizontal section taken on line 90 11—11 also in said Fig. 6. Fig. 12 is a side elevation of one of the sliding bolts of the lock; Fig. 13 is a bottom view of the same; Fig. 14 is a transverse section taken on line 14—14 in said Fig. 12; and Fig. 15 is a detail transverse vertical section taken on line 15—15 in said Fig. 12.

Similar characters of reference are employed in all of the above described views to indicate corresponding parts.

Referring now to the several figures of the drawings, the reference-character 1 indicates a bag-frame-section which is provided with the usual right-angled portion 2, and the reference-character 3 indicates an- 100 105 110

other bag-frame section which is provided with the usual right-angled portion or member 4, the said bag-frame-section 3 being adapted to be moved within the other bag-frame section 1 in the usual manner, when the two bag-frame sections are brought into their closed relation.

As indicated more particularly in Figs. 4, 9 and 10, the said bag-frame section 3 has 10 suitably secured to the inner or under surface of its right-angled portion or member 4, preferably by means of pins or rivets 5, the plate 6, said plate being provided with suitably formed and forwardly extending 15 portions 7 which are provided in their forward ends with suitably formed hook-shaped engaging or retaining members 8, as clearly illustrated.

As shown more particularly in Figs. 6, 7 20 and 8, the right-angled member or portion of the other frame-section 2 is provided with suitably disposed holes or openings 9, and with longitudinally extending openings or slots 10.

25 The reference-character 11 indicates the lock embodying the principles of my present invention, and the same comprises a suitably formed main or lower chambered shell or body 12 having the longitudinally extending sides or flanges 13 and ends 14, said ends 14 being provided with downwardly extending lugs or tongues 15 which are adapted to be inserted in the openings or holes 9 of the part 2 of the frame-section 35 1, and then bent at right angles against the under surface of said part 2, so as to secure the said chambered shell or box 12 upon the outer surface or face of the right angle portion 2 of said frame-section 1, which will 40 be clearly evident. In its upper surface, the said chambered shell or box 12 is provided with a centrally disposed hole or opening 16 and with a pair of longitudinally extending openings or slots 17 corresponding 45 to the longitudinally extending slots or openings 10 in the portion 2 of the frame-section 1, as clearly shown. The upper surface of the said chamber shell or box 12 is also provided with a pair of downwardly 50 extending lugs 18 which are forced out of the metal, substantially as shown, or other suitable fastening means with which may be suitably connected suitably formed coiled springs 19, substantially as shown and for 55 the purposes to be presently more fully described. The said chambered shell or box 12 is also provided in its upper surface with suitably disposed lug-receiving holes or openings 20 which are preferably arranged 60 in pairs, substantially as shown in Fig. 5 of the drawings, and are for the purpose of receiving suitably constructed retaining or fastening lugs or ears 21 which extend downwardly from the longitudinal sides or members of a suitable housing 22. As shown,

the said housing or shell 22 is opened at its opposite end-positions, as at 23, and is made with a centrally disposed and enlarged upper part or member 24, its upper portion 25 being preferably raised above the upper surface of the said housing or shell 22, and the said upper portion being provided with a suitably formed opening 26. Rotatably arranged within this enlarged central portion 24 of the said housing or shell 22 is a key-operated releasing-member or post which is made with a flat main body or member 27, and is provided upon its upper edge with a suitably formed and preferably cylindrically shaped turning member 28, the said so retaining member being arranged in an upwardly extending portion 25 of the shell or housing 22 and having a reduced cylindrical portion 29, extending into and rotatably arranged in the opening 26 of the said upwardly extending part of the shell or housing 22. The said turning member 28 is formed with a slot or opening 31 extending diametrically across the said member and provided with the centrally disposed key-receiving socket 30, in which may be inserted the lower end-portion of a suitably formed shank 32' of a key 32 for turning the said flat-body-member 27 of the said bolt-releasing member or post from its locking position shown in Figs. 2, 6 and 11, into its releasing position in a plane at right angles to that represented in said figures of the drawings, and as indicated in Figs. 3, 4, 7 and 8 of the drawings. To limit the oscillatory or rotary movement of the flat body or shank 27 of the said bolt-releasing-member or post and to cause the said flat-body-portion 27 to be retained at all times in its operative position, the lower chambered shell or body 12 is provided in its upper surface with a pair of upwardly extending lugs 32, substantially as shown in Fig. 11 of the drawings, which form suitable stops against which the said body-portion 27 is brought to limit its rotary movement in the two planes at right angles to each other, and to bring the edge-portions 33 of the said flat member 27 normally in alignment with the end-portions of the respective sliding bolts of the lock, substantially as shown in said Fig. 11 of the drawings and for the purposes to be presently more fully set forth. As shown, each sliding bolt comprises the chambered shell or portion 34 made at one end with an enlarged and laterally extending fingerpiece or portion 35 forming an integral part of the said shell 34, and the opposite end of the said shell being open as at 36. Suitably arranged within the chambered portion of the said shell 34, with its one end slightly projecting from the open end-portion 36 of the said shell, is a solid body-member 37 which is arranged between the inner faces of the lon-

gitudinally extending sides 38 of the said shell 34, and is immovably secured within said shell by means of suitably disposed fastening or holding tongues or lugs 39 which extend from the lower edge-portion of the sides 38 of said shells 34 and are bent over and clamped against the under surface of a reduced portion 40 of each bolt, as will be clearly evident from an inspection of several figures of the drawings.

Extending downwardly from the lower marginal edge of the reduced portion of each sliding bolt is a shank or post-like member 41 which is provided with a suitable perforation 42 or other suitable means for the attachment thereto, to each of said members 41, of the opposite end-portions of the previously mentioned coiled springs 19 which cause the said sliding bolts and parts connected therewith, under normal conditions, to be retained in the positions indicated in the Figs. 1, 2, 3, 6, 7 and 11 of the drawings.

From an inspection more particularly of Figs. 5, 6 and 7 of the drawings, it will be seen that the previously mentioned flat body-member or portion 27 of the bolt-retaining post is provided with a downwardly extending shank or portion 43 which extends into and is rotatably arranged in the centrally disposed opening or hole 16 in the upper surface of the shell or box 12, the said shank or portion 43 having suitably fitted and secured thereon a rectangular or other suitably shaped nut-like member 44, which has its sides in rotatable frictional engagement with the bolt-portion of a pair of springs 45 suitably arranged and secured within the chambered portion of said shell or member 12, as clearly shown in Fig. 6 of the drawings, and the purposes of said nut-like member and springs being to give a certain snapping action to the said bolt-releasing member or post at each quarter turn, as will be clearly understood from an inspection of said figures of the drawings. When the said oscillatory bolt-releasing member or post is in the position indicated in Figs. 4, 7 and 8 of the drawings, the edge-portions 33 of the flat body-part 27 having been moved out of engagement with the end-portions 40 of the sliding bolts, it will be clearly evident, that when the operator applies pressure upon the finger-pieces 35 of the respective bolts, the said bolts can be moved against the action

of the springs 19 in opposite directions, from the positions indicated in Figs. 3 and 7 to the position shown in Figs. 4 and 8, so as to withdraw the downwardly extending shanks or post-like members 41 from their held or locked relation with the hook-shaped engaging retaining members 8 of the frame-section 3, so that the two frame-sections can be separated and brought into their opened relation, as will be clearly evident. When the pressure is released from the finger-

pieces 35 of the said bolts, the springs 19 will return the said sliding bolts automatically into their normal initial positions, and the said hook-shaped engaging or retaining members 8, when the bag-frame sections are brought into their close relation, readily slide into their locked or holding engagement with the said posts or shanks 41 as will be clearly evident.

By inserting the shank 33' of the key 32' into the slotted or socketed portion 38 of the bolt-releasing member or post, and turning the body-portion 27 against the stops 32, so as to bring the edges 33 between and against the respective ends 40 of the sliding bolts, in the manner shown in Figs. 6 and 11 of the drawings, it will be evident that the said sliding bolts are immovably held by means of the said body-portion 27, and the two frame-sections of the bag-frame cannot be separated or brought into their opened relation. When, however, by means of the key, the said flat-body-portion or member 27 is turned against the said stops 22, into the dotted position indicated in Fig. 11 and as will be evident from an inspection of several figures of the drawings, the said sliding bolts are once more free to move so as to bring the said shanks or members 41 out of their holding or locked engagement with the hook-shaped members of the bag-frame section 3, so that the said frame-sections 1 and 3 can be separated or opened.

The operation of the various parts will be clearly understood from an inspection of the several figures of the drawings and it will be clearly evident that I have produced a simply constructed bag-frame lock, the parts of which have been reduced to a minimum and which can not easily get out of order.

I am fully aware that changes may be made in the arrangements and combinations of the various parts as well as in the details of the construction of the same without departing from the scope of my present invention as set forth in the appended claims. Hence, I do not limit my invention to the exact arrangements and combinations of the devices and parts as described in the foregoing specification, nor do I confine myself to the exact details of the construction of the said parts as illustrated in the accompanying drawings.

I claim:—

1. A bag-frame lock comprising a main chambered casing having means for attaching it upon a frame-section, said casing being provided with elongated openings, an upper housing secured upon the upper face of said casing, said housing being open at its opposite ends, a pair of spring-controlled bolts slidably arranged in said housing, each bolt having an end-portion extending from an opening in the end of the housing, a laterally enlarged finger-piece at the pro-

jecting end of each bolt for sliding each bolt and limiting its movement, a shank projecting downwardly from each bolt, each shank extending through an elongated opening of said casing and being movably arranged therein, and an oscillatory bolt-retaining member within said housing, said member being provided with a flat body-portion having its opposite marginal edges normally in alinement and in engagement with the opposing end-portions of said sliding bolts located within said housing, substantially as and for the purposes set forth.

2. A bag-frame lock comprising a main chambered casing having means for attaching it upon a frame-section, said casing being provided with elongated openings, an upper housing secured upon the upper face of said casing, said housing being opened at its opposite ends, a pair of spring-controlled bolts slidably arranged in said housing, each bolt having an end-portion extending from an opening in the end of the housing, a laterally enlarged finger-piece at the projecting end of each bolt for sliding each bolt and limiting its movement, a shank projecting downwardly from each bolt, each shank extending through an elongated opening of said casing and being movably arranged therein, and an oscillatory bolt-retaining member within said housing, said member being provided with a flat body-portion having its opposite marginal edges normally in alinement and in engagement with the opposing end-portions of said sliding bolts located within said housing, the said housing being provided in its upper surface with a centrally disposed opening, and said flat body-portion of the oscillatory bolt-retaining member being provided with an upper enlarged portion having a part rotatably arranged in said opening and being provided with a diametrically extending slot and a receiving socket for the insertion of the shank of a key therein, substantially as and for the purposes set forth.

3. A bag-frame lock comprising a main chambered casing having means for attaching it upon a frame-section, said casing being provided with elongated openings, an upper housing secured upon the upper face of said casing, said housing being open at its opposite ends, a pair of spring-controlled bolts slidably arranged in said housing, each bolt having an end-portion extending from an opening in the end of the housing, a laterally enlarged finger-piece at the projecting end of each bolt for sliding each bolt and limiting its movement, a shank projecting downwardly from each bolt, each shank extending through an elongated opening of said casing and being movably arranged therein, and an oscillatory bolt-retaining member within said housing, said member being provided with a flat body-portion

having its opposite marginal edges normally in alinement and in engagement with the opposing end-portions of said sliding bolts located within said housing, and upwardly extending lugs forced out of the upper surface of said main chambered casing, said lugs forming stops for limiting the oscillatory movement of said bolt-retaining member, substantially as and for the purposes set forth.

4. A bag-frame lock comprising a main chambered casing having means for attaching it upon a frame-section, said casing being provided with elongated openings, an upper housing secured upon the upper face of said casing, said housing being open at its opposite ends, a pair of spring-controlled bolts slidably arranged in said housing, each bolt having an end-portion extending from an opening in the end of the housing, a laterally enlarged finger-piece at the projecting end of each bolt for sliding each bolt and limiting its movement, a shank projecting downwardly from each bolt, each shank extending through an elongated opening of said casing and being movably arranged therein, and an oscillatory bolt-retaining member within said housing, said member being provided with a flat body-portion having its opposite marginal edges normally in alinement and in engagement with the opposing end-portions of said sliding bolts located within said housing, the said housing being provided in its upper surface with a centrally disposed opening, and said flat body-portion of the oscillatory bolt-retaining member being provided with an upper enlarged portion having a part rotatably arranged in said opening and being provided with a diametrically extending slot and a receiving socket for the insertion of the shank of a key therein, and upwardly extending lugs forced out of the upper surface of said main chambered casing, said lugs forming stops for limiting the oscillatory movement of said bolt-retaining member, substantially as and for the purposes set forth.

5. A bag-frame lock comprising a main chambered casing having means for attaching it upon a frame-section, said casing being provided with elongated openings, and a centrally disposed opening, an upper housing secured upon the upper face of said casing, said housing being open at its opposite ends, a pair of spring-controlled bolts slidably arranged in said housing, each bolt having an end-portion extending from an opening in the end of the housing, a laterally enlarged fingerpiece at the projecting end of each bolt for sliding each bolt and limiting its movement, a shank projecting downwardly from each bolt, each shank extending through an elongated opening of said casing and being movably arranged therein, and an oscillatory bolt-retaining member within said housing, said member

5 said housing, said member being provided with a flat body-portion having its opposite marginal edges normally in alinement and in engagement with the opposing end-portions of said sliding bolts located within said housing, a shank projecting downwardly from said flat body-portion, said shank extending through the centrally disposed opening of said main chambered casing and into 10 said casing, a nut-shaped member upon said shank, and a spring within said casing with which the side-portions of said nut-shaped member are adapted to be brought in slid- 15 able engagement, substantially as and for the purposes set forth.

6. A bag-frame lock comprising a main chambered casing having means for attaching it upon a frame-section, said casing being provided with elongated openings, and 20 a centrally disposed opening, an upper housing secured upon upper face of said casing, said housing being open at its opposite ends, a pair of spring-controlled bolts slidably arranged in said housing, each bolt having 25 an end-portion extending from an opening in the end of the housing, a laterally enlarged fingerpiece at the projecting end of each bolt for sliding each bolt and limiting its movement, a shank projecting down- 30 wardly from each bolt, each shank extending through an elongated opening of said casing and being movably arranged therein, an oscillatory bolt-retaining member within said housing, said member being pro- 35 vided with a flat body-portion having its opposite marginal edges normally in alinement and in engagement with the opposing end-portions of said sliding bolts located within said housing, a shank projecting 40 downwardly from said flat body-portion, said shank extending through the centrally disposed opening of said main chambered casing and into said casing, a nut-shaped member upon said shank, and a spring with- 45 in said casing with which the side-portions of said nut-shaped member are adapted to be brought in slidable engagement, the said housing being provided in its upper surface with a centrally disposed opening, and said 50 flat body-portion of the oscillatory bolt-retaining member being provided with an upper enlarged portion having a part rotatably arranged in said opening and being provided with a diametrically extending 55 slot and a receiving socket for the insertion of the shank of a key therein, substantially as and for the purposes set forth.

7. A bag-frame lock comprising a main chambered casing having means for attaching it upon a frame-section, said casing being provided with elongated openings, and a centrally disposed opening, an upper housing secured upon the upper face of said casing, said housing being open at its opposite 60 ends, a pair of spring-controlled bolts slid-

ably arranged in said housing, each bolt having an end-portion extending from an opening in the end of the housing, a laterally enlarged fingerpiece at the projecting end of each bolt for sliding each bolt and 70 limiting its movement, a shank projecting downwardly from each bolt, each shank extending through an elongated opening of said casing and being movably arranged therein, an oscillatory bolt-retaining member 75 within said housing, said member being provided with a flat body-portion having its opposite marginal edges normally in alinement and in engagement with the opposing end-portions of said sliding bolts located 80 within said housing, a shank projecting downwardly from said flat body-portion, said shank extending through the centrally disposed opening of said main chambered casing and into said casing, a nut-shaped member upon said shank, and a spring within 85 said casing with which the side-portions of said nut-shaped member are adapted to be brought in slidable engagement, and upwardly extending lugs forced out of the upper surface of said main chambered casing, said lugs forming stops for limiting the oscillatory movement of said bolt-retaining member, substantially as and for the purposes set forth. 90

8. A bag-frame lock comprising a main chambered casing having means for attaching it upon a frame-section, said casing being provided with elongated openings, and a centrally disposed opening, an upper housing secured upon the upper face of said casing, said housing being open at its opposite ends, a pair of spring-controlled bolts slidably arranged in said housing, each bolt having an end-portion extending from an opening in the end of the housing, a laterally enlarged fingerpiece at the projecting end of each bolt for sliding each bolt and limiting its movement, a shank projecting downwardly from each bolt, each shank extending through an elongated opening of said casing and being movably arranged therein, an oscillatory bolt-retaining member within said housing, said member being provided with a flat body-portion having its opposite marginal edges normally in alinement and in engagement with the opposing end-portions of said sliding bolts located within said housing, a shank projecting downwardly from said flat body-portion, said shank extending through the centrally disposed opening of said main chambered casing and into said casing, a nut-shaped member upon said shank, and a spring within said casing with which the side-portions of said nut-shaped member are adapted to be brought in slidable engagement, the said housing being provided in its upper surface with a centrally disposed opening, and said flat body-portion of the oscillatory bolt-retaining member being pro- 100 105 110 115 120 125 130

vided with an upper enlarged portion having a part rotatably arranged in said opening and being provided with a diametrically extending slot and a receiving socket for the insertion of the shank of a key therein, and upwardly extending lugs forced out of the upper surface of said main chambered casing, said lugs forming stops for limiting the oscillatory movement of said bolt-retaining member, substantially as and for the purposes set forth.

9. A bag-frame lock comprising a casing, and a sliding bolt, said bolt consisting of a chambered shell, said shell being open at one end, and being provided at its other end with a laterally enlarged fingerpiece, a solid body arranged within said chambered shell, and a downwardly extending holding catch-retaining shank connected with said solid body, substantially as and for the purposes set forth.

10. A bag-frame lock comprising a casing, and a sliding bolt, said bolt consisting of a chambered shell, said shell being open at one end, and being provided at its other end with a laterally enlarged fingerpiece, a solid body arranged within said chambered shell, retaining lugs extending from the lower marginal edge-portions of said shell, said lugs being bent beneath said solid body for securing it in place in said shell, and a downwardly extending holding catch-retaining shank connected with said solid body, substantially as and for the purposes set forth.

35 11. A bag-frame lock comprising a main chambered casing having means for attaching it upon a frame-section, said casing being provided with elongated openings, and a centrally disposed opening, an upper housing secured upon the upper face of said casing, a pair of spring-controlled bolts slidably arranged in said housing, each bolt consisting of a chambered shell, said shell being open at one end, and being provided at the other end with a laterally enlarged fingerpiece, a solid body arranged within each chambered shell, retaining lugs extending from the lower marginal edge-portions of said shells, said lugs being bent beneath the said solid bodies for securing said bodies within the respective shells, a holding catch-retaining shank connected with each solid body and extending through an elongated opening of said main chambered casing and being movably arranged therein, an oscillatory bolt-retaining member within said housing, said member being provided with a flat body-portion having its opposite marginal edges normally in alinement and in engagement with the opposing end-portions of said sliding bolts, a shank projecting downwardly from said flat body-portion, said shank extending through the centrally disposed opening of said main chambered casing and into said casing, a nut-shaped mem-

ber upon said shank, and a spring within said casing with which the side-portions of said nut-shaped member are adapted to be brought in slidable engagement, substantially as and for the purposes set forth. 70

12. A bag-frame lock comprising a main chambered casing having means for attaching it upon a frame-section, said casing being provided with elongated openings, and a centrally disposed opening, an upper housing secured upon the upper face of said casing, a pair of spring-controlled bolts slidably arranged in said housing, each bolt consisting of a chambered shell, said shell being open at one end, and being provided at the other end with a laterally enlarged fingerpiece, a solid body arranged within each chambered shell, retaining lugs extending from the lower marginal edge-portions of said shells, said lugs being bent beneath the said solid bodies for securing said bodies within the respective shells, a holding catch-retaining shank connected with each solid body and extending through an elongated opening of said main chambered casing and being movably arranged therein, an oscillatory bolt-retaining member within said housing, said member being provided with a flat body-portion having its opposite marginal edges normally in alinement and in engagement with the opposing end-portions of said sliding bolts, a shank projecting downwardly from said flat body-portion, said shank extending through the centrally disposed opening of said main chambered casing and into said casing, a nut-shaped member upon said shank, and a spring within said casing with which the side-portions of said nut-shaped member are adapted to be brought in slidable engagement, the said housing being provided in its upper surface with a centrally disposed opening, and said flat body-portion of the oscillatory bolt-retaining member being provided with an upper enlarged portion having a part rotatably arranged in said opening and being provided with a diametrically extending slot and a receiving socket for the insertion of the shank of a key therein, substantially as and for the purposes set forth. 100 110 115

13. A bag-frame lock comprising a main chambered casing having means for attaching it upon a frame-section, said casing being provided with elongated openings, and a centrally disposed opening, an upper housing secured upon the upper face of said casing, a pair of spring-controlled bolts slidably arranged in said housing, each bolt consisting of a chambered shell, said shell being open at one end, and being provided at the other end with a laterally enlarged fingerpiece, a solid body arranged within each chambered shell, retaining lugs extending from the lower marginal edge-portions of said shells, said lugs being bent beneath 120 125 130

the said solid bodies for securing said bodies within the respective shells, a holding catch-retaining shank connected with each solid body and extending through an elongated opening of said main chambered casing and being movably arranged therein, an oscillatory bolt-retaining member within said housing, said member being provided with a flat body-portion having its opposite marginal edges normally in alinement and in engagement with the opposing end-portions of said sliding bolts, a shank projecting downwardly from said flat body-portion, said shank extending through the centrally disposed opening of said main chambered casing and into said casing, a nut-shaped member upon said shank, and a spring within said casing with which the side-portions of said nut-shaped member are adapted to be brought in slidable engagement, and upwardly extending lugs forced out of the upper surface of said main chambered casing, said lugs forming stops for limiting the oscillatory movement of said bolt-retaining member, substantially as and for the purposes set forth.

14. A bag-frame lock comprising a main chambered casing having means for attaching it upon a frame-section, said casing being provided with elongated openings, and a centrally disposed opening, an upper housing secured upon the upper face of said casing, a pair of spring-controlled bolts slidably arranged in said housing, each bolt consisting of a chambered shell, said shell being open at one end, and being provided at the other end with a laterally enlarged fingerpiece, a solid body arranged within each chambered shell, retaining lugs extending from the lower marginal edge-portions of said shells, said lugs being bent beneath the said solid bodies for securing said bodies within the respective shells, a holding catch-retaining shank connected with each solid body and extending through an elongated opening of said main chambered casing and being movably arranged therein, an oscillatory bolt-retaining member within said housing, said member being provided with a flat body-portion having its opposite marginal edges normally in alinement and in engagement with the opposing end-portions of said sliding bolts, a shank projecting downwardly from said flat body-portion, said shank extending through the centrally disposed opening of said main chambered casing and into said casing, a nut-shaped member upon said shank, and a spring within said casing with which the side-portions of said nut-shaped member are adapted to be brought in slidable engagement, the said housing being provided in its upper surface with a centrally disposed opening, and said flat body-portion of the oscillatory bolt-retaining member being provided with an upper enlarged portion having a part rotatably arranged in said opening and being provided with a diametrically extending slot and a receiving socket for the insertion of the shank of a key therein, and upwardly extending lugs forced out of the upper surface of said main chambered casing, said lugs forming stops for limiting the oscillatory movement of said bolt-retaining member, substantially as and for the purposes set forth.

In testimony, that I claim the invention set forth above I have hereunto set my hand this 4th day of September, 1908.

BENNO VOM EIGEN.
